United States Patent Office

Des. 208,389

Patented Aug. 22, 1967

208,389

HOSE COUPLING

Clayton H. Skinner, Buffalo, N.Y., assignor to
Hewitt-Robins Incorporated, Stamford, Conn.

Filed Nov. 18, 1965, Ser. No. 88,142

Term of patent 14 years

(Cl. D91—3)

FIG. 1

FIG. 4

FIG. 3

FIG. 2

FIG. 5

FIG. 1 is a perspective view from one end of hose coupling, showing my new design.

FIG. 2 is another perspective view from the opposite end of the hose coupling shown in FIG. 1.

FIG. 3 is an end elevational view of the design according to FIG. 1.

FIG. 4 is an end elevational view of the design according to FIG. 2.

FIG. 5 is a side elevational view of the design according to FIGS. 1 and 2.

The dominant features of my design reside in the portions shown in full lines.

I claim:

The ornamental design for a hose coupling, as shown and described.
